UNITED STATES PATENT OFFICE.

JOHN W. MEAKER, OF CHICAGO, ILLINOIS, ASSIGNOR TO AMERICAN STEEL & WIRE COMPANY, OF CLEVELAND, OHIO, A CORPORATION OF NEW JERSEY.

WIRE-ATTACHING CLIP.

Application filed September 20, 1923. Serial No. 663,828.

To all whom it may concern:

Be it known that I, JOHN W. MEAKER, a citizen of the United States, residing at Chicago, in the county of Cook and State 5 of Illinois, have invented certain new and useful Improvements in Wire-Attaching Clips, of which the following is a specification.

This invention relates to a new and improved wire attaching clip and more particularly to a clip adapted for use in attaching fence wires to fence posts of types having wire engaging flanges and webs directed approximately at right angles to the 15 flanges.

Clips of this character must be adapted for easy and rapid application to the wire and post and capable of making proper retaining contact with the post and wire.

It is an object of the present invention to provide a new and improved wire retaining clip which is simple in design and adapted for easy and rapid application.

It is a further object to provide a clip, 25 the wire engaging portion of which is so formed as to provide effective retaining engagement with the wire without deformation of the wire or clip.

Other and further objects will appear as 30 the description proceeds.

I have illustrated certain preferred embodiments of my invention in the accompanying drawings, in which—

Figure 1 is a fragmentary view of a portion 35 of a fence post with wires attached thereto by means of my clip;

Figure 2 is a view of Figure 1 as seen from the left;

Figure 3 is a section taken on line 3—3 40 of Figure 1;

Figure 4 is a perspective view of the clip shown in Figures 1 to 3;

Figure 5 is a view similar to Figure 4 but showing a modified form of clip; and

Figure 6 is a view similar to Figure 3 but showing the form of clip shown in Figure 5.

The clip has been shown used in connection with a T-shaped post 11 having serrations formed on the edges of the flange, these serrations having high points 12 and low points 13. As shown in the drawings, the fence wire 14 will normally lie across opposite depressions or low points 13.

My improved clip, in the form shown in

Figure 4, is provided with the flange engaging hook 15, the post edge engaging straight portion 16, the wire engaging arc 17, the second straight post edge engaging portion 18 and the securing portion 19. As 60 shown in Figure 3, when the clip is applied to the post to secure a wire, the hook portion 15 is hooked behind the one side of a flange 20 of the post. The straight portion 16 lies across the face of the post upon one 65 side of the wire 14, the arc 17 crosses the wire at an angle and the second straight portion 18 lies upon the opposite side of the wire 14 and adjacent thereto. The portion 19 is bent around the bulb 21 on the 70 rear of the web of the post. It will be noted, as clearly shown in Figures 3 and 6, that neither the clip nor the wire engages the flat face of the post.

The form of clip shown in Figures 5 and 75 6 is similar to that of the other figures and is provided with the flange engaging hook 15', the wire engaging arc 17' and the straight portions 16' and 18'. Instead of the long portion 19, however, this form of 80 clip is provided with a portion 22 adapted to be bent around the edge of the flange opposite to the portion 15, as clearly shown in Figure 6.

With types of clips having straight portions adapted to extend across the face of the post, the clip extending diagonally across the post is greater in length than the width of the post and easily works loose thereon, permitting the wire to move vertically of 90 the post. In the present form of clip, the arc 17 closely surrounds the wire and the opposite side portions 16 and 18 lie adjacent to and parallel with the wire. The clip thus firmly and positively engages the wire and 95 retains it in place upon the post in a manner adapted to adequately prevent vertical displacement.

The clip is capable of rapid application by merely bending the portion 19 around the rear of the post or the portion 22 around the rear of the flange and, particularly when applied to posts of the general type shown, is efficient in preventing movement of the wire vertically of the post, as well as providing the desired relative freedom of movement of the wire laterally of the post.

I claim:

1. A wire attaching clip for use with fence posts having a wire engaging flange, the clip 111

- having a hook adapted to engage an edge of a post flange, a portion adapted to extend across the flange to retain wire against the flange, and an end portion adapted to be bent 5 around another portion of a post, the wire retaining portion having its central portion formed with a relatively short wire retaining arc formed therein, the parts of the wire retaining portion upon either side of the arc 10 being formed to lie approximately parallel to a post flange.
2. A wire attaching clip for use with fence posts having a wire engaging flange, the clip having a hook adapted to engage an edge of 15 a post flange, a portion adapted to extend across the flange to retain wire against the flange, and an end portion adapted to be bent around another portion of a post, the wire retaining portion having its central 20 portion formed with a relatively short wire retaining arc formed therein, said arc approximately equaling in depth the diameter of the wire, the parts of the wire retaining portion upon either side of the arc being 25 formed to lie approximately parallel to the wire and to a post flange.
3. A wire attaching clip for use with fence posts having a wire engaging flange, the clip having a hook adapted to engage an edge of 30 a post flange, a portion adapted to extend across the flange to retain wire against the flange, and an end portion adapted to be bent around toward the rear of a post, the wire retaining portion having its central portion formed with a relatively short wire retaining arc formed therein, the parts of the wire retaining portion upon either side of the arc 35 being formed to lie approximately parallel to a post flange, and being offset relative to each other whereby they lie in approximately parallel spaced horizontal planes.
4. A wire attaching clip for use with fence posts having a wire engaging flange, the clip having a hook adapted to engage an edge of a post flange, a portion adapted to extend across the flange to retain wire against the flange, and an end portion adapted to be bent around toward the rear of a post, the wire retaining portion having its central portion formed with a relatively short wire retaining arc formed therein, the parts of the wire retaining portion upon either side of the arc 40 being formed to lie approximately parallel to a post flange, and being offset relative to each other whereby they lie in approximately parallel spaced horizontal planes.
5. A wire attaching clip for use with fence posts having a wire engaging flange, the clip having a hook adapted to engage an edge of a post flange, a portion adapted to extend across the flange to retain wire against the flange, and an end portion adapted to be bent around toward the rear of a post, the wire retaining portion having its central portion formed with a relatively short wire retaining arc formed therein, the parts of the wire retaining portion upon either side of the arc 45 being formed to lie approximately parallel to a post flange, and being offset relative to each other whereby they lie in approximately parallel spaced horizontal planes.
6. A wire attaching clip for use with fence posts having a wire engaging flange, the clip having a hook adapted to engage an edge of a post flange, a portion adapted to extend across the flange to retain wire against the flange, and an end portion adapted to be bent around toward the rear of a post, the wire retaining portion having its central portion formed with a relatively short wire retaining arc formed therein, the parts of the wire retaining portion upon either side of the arc 50 being formed to lie approximately parallel to a post flange, and being offset relative to each other whereby they lie in approximately parallel spaced horizontal planes.
7. A wire attaching clip for use with fence posts having a wire engaging flange, the clip having a hook adapted to engage an edge of a post flange, a portion adapted to extend across the flange to retain wire against the flange, and an end portion adapted to be bent around toward the rear of a post, the wire retaining portion having its central portion formed with a relatively short wire retaining arc formed therein, the parts of the wire retaining portion upon either side of the arc 55 being formed to lie approximately parallel to a post flange, and being offset relative to each other whereby they lie in approximately parallel spaced horizontal planes.
8. A wire attaching clip for use with fence posts having a wire engaging flange, the clip having a hook adapted to engage an edge of a post flange, a portion adapted to extend across the flange to retain wire against the flange, and an end portion adapted to be bent around toward the rear of a post, the wire retaining portion having its central portion formed with a relatively short wire retaining arc formed therein, the parts of the wire retaining portion upon either side of the arc 60 being formed to lie approximately parallel to a post flange, and being offset relative to each other whereby they lie in approximately parallel spaced horizontal planes.

Signed at Chicago, Illinois, this 17th day of September, 1923.

JOHN W. MEAKER.
